UNITED STATES PATENT OFFICE.

DAVID YADGIR, OF CHICAGO, ILLINOIS.

REVERSIBLE WINDOW.

1,351,316.

Specification of Letters Patent. Patented Aug. 31, 1920.

Application filed February 16, 1920. Serial No. 359,128.

To all whom it may concern:

Be it known that I, DAVID YADGIR, a subject of the Shah of Persia, and a resident of Chicago, in the county of Cook, State of Illinois, have invented certain new and useful Improvements in Reversible Windows, of which the following is a specification.

This invention relates to that class of reversible windows in which the sashes are adapted to slide vertically and pivot horizontally in the window frame as the operator may require.

The objects of the present improvement are:

To provide a structural formation and association of parts whereby an effective and very substantial guiding connection between the window frame and sashes is attained and with which the weather is excluded in an effective manner.

To provide in connection with such guiding means, a simple and substantial pivotal means adapted for coacting operation therewith, and with which a safe and convenient pivotal movement of the sashes can be effected, all as will hereinafter more fully appear.

In the accompanying drawings:

Figure 1, is a fragmentary elevation with parts in section, illustrating the preferred arrangement of the present invention.

Fig. 2, is a perspective view of one of the guide rails in a detached condition.

Fig. 3, is a similar view of the guiding means for said rail.

Fig. 4, is a detail horizontal, section on line 4—4. Fig. 1.

Figs. 5 and 6, are detail horizontal sections on line 5—5, Fig. 1 illustrating the respective engaged and disengaged condition of the guide rails in the different operations of the sash.

Fig. 7, is a detail sectional elevation on line 7—7, Fig. 6.

Like reference numerals indicate like parts in the different views.

Referring to the drawings, 1 designates the window frame, which as in the present type of reversible windows is provided with vertical guide grooves 2, for the guidance of the upper and lower window sashes 3, 4, in place of the usual vertical guide strip and parting bead employed in connection with the ordinary vertically moving window sashes.

The respective sashes 3, 4 are formed with

vertical recesses 5, preferably extending the full length of the vertical rails of the sashes and which are adapted to register with the guide grooves 2, of the window frame. 60 Each recess 5 opens through a vertical end wall of a sash rail and is provided with marginal opposed flanges 6, which in the present invention constitute stops and guides as hereinafter set forth.

The recesses 5 are preferably formed as large in cross section as the strength and material required in said vertical sash rails will permit, and so that the hereinafter described guide rails which fit in said recesses 70 may be of a corresponding size in cross section.

7 designates one of the vertical guide rails above referred to, arranged in an aforesaid vertical recess 5 of a window sash and adapted to have limited sliding movement in said recess, as illustrated in Figs. 5 and 6. Each guide rail 7 is formed with vertical ribs or flanges 8 adapted for sliding contact with the opposed vertical walls of 80 a recess 5 and for a stop engagement with the flanges 6 of said recess to limit the independent outward movement of the guide rail 7 in relation to the sash rail in which it is mounted.

In the normal and active position of the guide rail 7, illustrated in Fig. 5 its outer portion has engagement in a guide groove 2 of the window frame, to constitute in connection with a similar construction at the other end of the sash, the sole guiding means between the sash and frame in the ordinary vertical movement of said sash, and constructed in the manner shown and described, provides a substantial and effective guiding means, with ample provision against lateral movement, wind leakage, etc.

9 designates a rack bar fixedly secured to a vertical guide bar 7 and adapted for operative engagement with a pinion 10 carried 100 by a manually rotatable shaft 11 journaled in the window sash rail, and adapted to impart movement to said guide rail 7 into and out of its guide groove 2 of the window frame, as may be required in attaining a position of parts which admits of a pivotal operation of the window sash, or a return of said parts to a position in which the window sash is confined to its normal vertically sliding movement. No claim to 110 novelty to such guide rail operating means, is made and any other usual and ordinary

operating mechanism may be employed instead as the judgment of the constructor may direct.

- 12 and 13 designate vertically separated and horizontally arranged guide stems, carried on a base plate 14 secured to a vertical sash rail with the said guide stems extending horizontally through the material of said sash rail and through the midwidth of an aforesaid vertical recess 5 of said rail, and so that stems 12 and 13 may constitute horizontal guides for the guide rail 7 aforesaid by means of guide orifices in said rail as shown. With such construction a ready assemblage of parts can be achieved, as well as a subsequent disassemblage for the purpose of repair and replacement, in that by an unfastening and removal of the base plate 14 and associated guide stems 12, 13 the sash can be removed from the window frame for access to all parts. In the preferred form of the present improvement, the respective upper and lower guide stems 12 extend to a plane approximately even with the end of the sash rail, so that in a pivotal movement of a window sash said stems 12 may clear the adjacent face of the window frame, while the central guide stem 13 extends beyond such end of the sash rail and into a guide groove 2 of the window frame, with its free end portions preferably connected to the sash cord 15 arranged in the usual manner and having the usual sash pulley and counter weight connections.
- 35 The aforesaid central guide stems 13 constitute the pivot means of a widow sash in a pivotal movement of the same, and with a view to afford pivot bases for said stems, the window frame is formed with a plurality of horizontal orifices 16 which intersect the aforesaid guide grooves 2 of the window frame and are adapted to receive the removable bearing strips now to be described.
- 40 17 designates one of the bearing strips above referred to, adapted for insertion in the aforesaid orifice 16 of the window frame and preferably formed with an obliquely arranged bearing recess 18 in its upper edge adapted to receive and hold a central stem 13, when the sash is lowered to attain pivotal engagement of the parts. In the present improvement any required number of the orifices 16 may be provided in vertically spaced relation, so that the window sashes 50 may have pivotal movements at different heights to meet the varied requirements and conditions met with in a general use of the invention.
- 45 As applied to window structure the here- 60 tofore described arrangement of parts is duplicated at the opposite side of the window frame and sashes, and the described adjustments of the parts will be made in unison at both sides before effecting the different 65 operations of the sashes above set forth.

Having thus fully described my said invention what I claim as new and desire to secure by Letters Patent is:—

1. In a reversible window, the combination of a window frame provided with a vertical guide groove, a window sash formed with an open recess along an end of a vertical rail of the sash, a guide rail movable in said recess and adapted to engage in the guide groove of the window frame, a horizontal guide stem carried by the sash and having guiding engagement with said guide rail, said guide stem extending through the guide rail and into the guide groove of the window frame to constitute a pivot for the sash, a base plate carrying said stem and adapted for attachment to an outer face of the sash rail, a removable bearing strip adapted for engagement with said stem, and means for imparting sliding movement to said guide rail. 70
2. In a reversible window, the combination of a window frame provided with a vertical guide groove, a window sash formed with an open recess along an end of a vertical rail of the sash, a guide rail movable in said recess and adapted to engage in said guide groove of the window frame, a vertical series of horizontal guide stems extending entirely through the sash and having 75 guiding engagement with said guide rail, one of said guide stems extending into the guide groove of the window frame and constituting a pivot for the sash, a base plate carrying said guide stems and adapted for attachment to an outer face of the sash rail, a removable bearing strip adapted for engagement with said stem, and means for imparting sliding movement to said guide rail. 80
3. In a reversible window, the combination of a window frame provided with a vertical guide groove, a window sash formed with an open recess along an end of a vertical rail of the sash, said recess having flanges at its open side, a guide rail movable in 85 said recess and adapted to engage in the guide groove of the window frame, said guide rail having vertical flanges along its length, a horizontal guide stem carried by the sash and having guiding engagement with said guide rail, said guide stem extending into the guide groove of the window frame and constituting a pivot for the sash, a removable bearing strip adapted for engagement with said stem, and means for imparting sliding movement to said guide rail. 90
4. In a reversible window, the combination of a window frame provided with a vertical guide groove, a window sash formed with an open recess along an end of a vertical rail of the sash, said recess having flanges at its open side, a guide rail movable in 95 said recess and adapted to engage in the guide groove of the window frame, said guide rail having vertical flanges along its length, a horizontal guide stem carried by the sash and having guiding engagement with said guide rail, said guide stem extending into the guide groove of the window frame and constituting a pivot for the sash, a removable bearing strip adapted for engagement with said stem, and means for imparting sliding movement to said guide rail. 100
5. In a reversible window, the combination of a window frame provided with a vertical guide groove, a window sash formed with an open recess along an end of a vertical rail of the sash, said recess having flanges at its open side, a guide rail movable in 105 said recess and adapted to engage in the guide groove of the window frame, said guide rail having vertical flanges along its length, a horizontal guide stem carried by the sash and having guiding engagement with said guide rail, said guide stem extending into the guide groove of the window frame and constituting a pivot for the sash, a removable bearing strip adapted for engagement with said stem, and means for imparting sliding movement to said guide rail. 110
6. In a reversible window, the combination of a window frame provided with a vertical guide groove, a window sash formed with an open recess along an end of a vertical rail of the sash, said recess having flanges at its open side, a guide rail movable in 115 said recess and adapted to engage in the guide groove of the window frame, said guide rail having vertical flanges along its length, a horizontal guide stem carried by the sash and having guiding engagement with said guide rail, said guide stem extending into the guide groove of the window frame and constituting a pivot for the sash, a removable bearing strip adapted for engagement with said stem, and means for imparting sliding movement to said guide rail. 120
7. In a reversible window, the combination of a window frame provided with a vertical guide groove, a window sash formed with an open recess along an end of a vertical rail of the sash, said recess having flanges at its open side, a guide rail movable in 125 said recess and adapted to engage in the guide groove of the window frame, said guide rail having vertical flanges along its length, a horizontal guide stem carried by the sash and having guiding engagement with said guide rail, said guide stem extending into the guide groove of the window frame and constituting a pivot for the sash, a removable bearing strip adapted for engagement with said stem, and means for imparting sliding movement to said guide rail. 130

5 rail having vertical flanges along its length, a vertical series of horizontal guide stems carried by the sash and having guiding engagement with said guide rail, one of said 5 guide stems extending into the guide groove of the window frame and constituting a pivot for the sash, a removable bearing strip adapted for engagement with said stem, and means for imparting sliding movement to said guide rail.

10 6. In a reversible window, the combination of a window frame provided with a vertical guide groove, a window sash formed with an open recess along an end of a vertical rail of the sash, a guide rail movable in said recess and adapted to engage in said guide groove of the window frame, a vertical series of horizontal guide stems, a base plate carrying said stems and secured to the sash, said guide stems having guiding engagement with said guide rail, one of said 15 guide stems extending into the guide groove of the window frame and constituting a pivot for the sash, a removable bearing strip 20 adapted for engagement with said stem, and means for imparting sliding movement to said guide rail.

25 7. In a reversible window, the combination of a window frame provided with a vertical guide groove, a window sash formed with an open recess along an end of a vertical rail of the sash, said recess having flanges at its open side, a guide rail movable in said recess and adapted to engage in the 30 guide groove of the window frame, said guide rail having vertical flanges along its length, a vertical series of horizontal guide stems, a base plate carrying said stems and secured to the sash, said guide stems having 35 guiding engagement with said guide rail, one of said guide stems extending into the guide groove of the window frame and constituting a pivot for the sash, a removable bearing strip adapted for engagement 40 with said stem, and means for imparting sliding movement to said guide rail.

45 8. In a reversible window, the combination of a window frame provided with a vertical guide groove, a window sash formed with an open recess along an end of a vertical rail of the sash, a guide rail movable in said recess and adapted to engage in the guide groove of the window frame, a horizontal guide stem carried by the sash and having guiding engagement with said guide rail, said guide stem extending into the 50 guide groove of the window frame and constituting a pivot for the sash, a removable bearing strip adapted for engagement with said stem, the window frame having a horizontal orifice intersecting its guide groove and adapted to receive said bearing strip, and means for imparting sliding movement to said guide rail.

55 9. In a reversible window, the combination

of a window frame provided with a vertical guide groove, a window sash formed with an open recess along an end of a vertical rail of the sash, a guide rail movable in said recess and adapted to engage in said 70

guide groove of the window frame, a vertical series of horizontal guide stems carried by the sash and having guiding engagement with said guide rail, one of said guide stems extending into the guide groove of the window frame and constituting a pivot for the sash, a removable bearing strip adapted for engagement with said stem, the window frame having a horizontal orifice intersecting its guide groove and adapted to receive 75 said bearing strip, and means for imparting sliding movement to said guide rail.

80 10. In a reversible window, the combination of a window frame provided with a vertical guide groove, a window sash formed with an open recess along an end of a vertical rail of the sash, a guide rail movable in said recess and adapted to engage in the guide groove of the window frame, a horizontal guide stem carried by the sash and having guiding engagement with said guide rail, said guide stem extending into the guide groove of the window frame and constituting a pivot for the sash, a removable bearing strip formed with a pivot recess in 85 its upper edge for engagement with said stem, the window frame having a horizontal orifice intersecting its guide groove and adapted to receive said bearing strip, and means for imparting sliding movement to 90 said guide rail.

95 11. In a reversible window, the combination of a window frame provided with a vertical guide groove, a window sash formed with an open recess along an end of a vertical rail of the sash, a guide rail movable in said recess and adapted to engage in the guide groove of the window frame, a vertical series of horizontal guide stems carried by the sash and having guiding engagement with said guide rail, one of said guide stems extending into the guide groove of the window frame and constituting a pivot for the sash, a removable bearing strip formed with a pivot recess in 105 its upper edge for engagement with said stem, the window frame having a horizontal orifice intersecting its guide groove and adapted to receive said bearing strip, and means for imparting sliding movement to 110 said guide rail.

115 12. In a reversible window, the combination of a window frame provided with a vertical guide groove, a window sash formed with an open recess along an end of a vertical rail of the sash, a guide rail movable in said recess and adapted to engage in the guide groove of the window frame, a horizontal guide stem extending entirely through the sash and having guiding engagement with said guide rail, said guide stem extend- 125

ing into the guide groove of the window frame and adapted for pivotal attachment to a sash cord, a base plate carrying said guide stem and adapted for attachment to an outer face of the sash rail, and means for imparting sliding movement to said guide rail.

12. In a reversible window, the combination of a window frame provided with a vertical guide groove, a window sash formed with an open recess along an end of a vertical rail of the sash, a guide rail movable in said recess and adapted to engage in said guide groove of the window frame, a vertical series of horizontal guide stems extending entirely through the sash and having guiding engagement with said guide rail, one of said guide stems extending into the guide groove of the window frame and adapted for pivotal attachment to a sash cord, a base plate carrying said guide stems and adapted for attachment to an outer face of the sash rail, and means for imparting sliding movement to said guide rail.

13. In a reversible window, the combination of a window frame provided with a vertical guide groove, a window sash formed with an open recess along an end of a vertical rail of the sash, a guide rail movable in said recess and adapted to engage in the guide groove of the window frame, a horizontal guide stem extending entirely through

the sash and having guiding engagement with said guide rail, said guide stem extending into the guide groove of the window frame and adapted for pivotal attachment to a sash cord, a base plate carrying said guide stem and adapted for attachment to an outer face of the sash rail, a removable bearing strip providing a pivot bearing for said stem, and means for imparting sliding movement to said guide rail.

14. In a reversible window, the combination of a window frame provided with a vertical guide groove, a window sash formed with an open recess along an end of a vertical rail of the sash, a guide rail movable in said recess and adapted to engage in said guide groove of the window frame, a vertical series of horizontal guide stems extending entirely through the sash and having guiding engagement with said guide rail, one of said guide stems extending into the guide groove of the window frame and adapted for pivotal attachment to a sash cord, a base plate carrying said guide stems and adapted for attachment to an outer face of the sash rail, a removable bearing strip providing a pivot bearing for said stem, and means for imparting sliding movement to said guide rail.

Signed at Chicago, Illinois, this 14th day of February, 1920.

DAVID YADGIR.
